Primary Examiner — Karen S Acker*Assistant Examiner* — Steven B Reinholdt, Jr.(74) *Attorney, Agent, or Firm* — Chainey P. Singleton(57) **CLAIM**

The ornamental design for an ammunition cartridge, as shown and described.

DESCRIPTION

FIG. 1 is an isometric view of an ammunition cartridge showing my new design.

FIG. 2 is a top view of the ammunition cartridge of FIG. 1. FIG. 3 is a cross-sectional view taken along line 3-3 in FIG. 2 of the ammunition cartridge of FIG. 1; and, FIG. 4 is a side view of the ammunition cartridge of FIGS. 1.

The broken lines depict portions of the ammunition cartridge that form no part of the claim.
